C. E. C. EDEY

STOVE OR FURNACE

Filed Feb. 13, 1926

INVENTOR.

CHARLES E.C. EDEY

BY

Frederick H. Taylor

ATTORNEY.

UNITED STATES PATENT OFFICE.

CHARLES E. C. EDEY, OF LOS ANGELES, CALIFORNIA.

STOVE OR FURNACE.

Application filed February 13, 1926. Serial No. 88,036.

My invention relates to heating systems and appliances associated therewith, as well as the process for heating buildings, and more particularly to a furnace or stove in which coal or wood may alternatively be burned, the air being heated by convection currents set up in said buildings by reason of the cooler air being conveyed to said stove or furnace, below the ash pit and to the rear of said stove or furnace, and thence to the stack, cooling the same, and thus conserving the heat so as to produce an exceedingly economical heating plant without the use of expensive piping.

It accordingly is an object of my invention to provide a novel form of heating appliance having a set of grate bars upon which a coal fire may be built, said bars being adapted to be lowered to form side walls to coat with a removable ash pit so that wood may be burned therein, a draft regulating means being associated with said ash pit for starting the fire only, said means being closed after the fire has started, and a set of passages associated with the bottom and rear of said appliance, said passages being used to set up convection currents in the building in which said appliance is positioned, the air entering said flues never reaching the fire.

It is also within the province of my invention to provide an additional set of openings in the rear wall associated with my novel form of heating appliance for the purpose of providing an additional exit for the products of combustion to the stack.

It is moreover within the province of my invention to provide a novel means of shaking the grate bars and also for lowering them so said grate bars will form side walls to coat with the ash pit so wood may be burned in my stove or furnace.

It is also an object of my invention to provide a novel form of apparatus which is simple in character, composed of a minimum number of parts, not easy to get out of order, economical and efficient in operation, inexpensive to manufacture, and one which will thoroughly and reliably, effect the objects intended.

Further objects and advantages of my invention will become more apparent as the description thereof proceeds.

Reference is had to the accompanying drawings, in which similar reference char-

acters denote similar parts. In the drawings,

Fig. 1 is a front elevational view of my invention,

Fig. 2 is a longitudinal cross-sectional view on the line 2—2, Fig. 1, looking in the direction of the arrows,

Fig. 3 is a transverse cross-sectional view on the line 3—3, Fig. 2, also looking in the direction of the arrows,

Fig. 4 is a fragmentary transverse cross-sectional view, showing the grate bars collapsed to form side walls to coat with the ash pit so that wood may be burned therein, and

Fig. 5 is a similar view showing a modification.

Describing my invention more in detail, I provide a casing 1 of any preferred configuration and constructed of any suitable material, either cast metal or brick, which casing is equipped with a top 24 associated therewith in any manner preferred, a stack 6 being associated with said top as desired, or with the casing 1 as preferred, for carrying away the products of combustion.

Preferably, the casing 1 is partitioned off as indicated more particularly in Fig. 2, to provide a rear wall 27 and a bottom wall 28, defining a rear passage 5 and a bottom passage 4. Of course it is to be understood that these passages may be arranged in a different manner.

A fire pot or chamber 25, equipped, if desired, with walls of refractory material, is positioned within the space defined by the walls 27 and 28, and a set of grate bars 2 form the bottom of said fire pot, upon which a coal fire may be built. It will be understood that if desired grate bars of different construction and number may be provided instead of those shown.

The grate bars 2 are preferably pivoted on one side to a bar or rod associated in any manner desired with the stove or furnace construction, which bars or rods are equipped externally of said stove or furnace with a grate shaking or lowering means 9, preferably in the shape of rectangular bars, though this is immaterial, an appliance or bail 8, preferably detachable from the bars 9 being provided as a handle to shake said grate bars. It will be understood, however, that any means, either integral with, or associated in any manner with the bars 9 may be sub-

stituted for the construction just described, and still remain within the province of my invention.

If desired, the front of the furnace or stove may be equipped with one or more clean-out doors 7 of any character, said door being provided with a knob or handle 10 for manipulating the same, the fire chamber 26 being reached by means of said door.

10 The ash pit is positioned below the chamber 25 and the grate bars 2, and said ash pit contains a removable receptacle 3 for receiving the ashes from the coal burned on said grate bars, and also functions as a chamber or fire pot within which wood may be burned, in this instance the grate bars 2 taking the position shown in Fig. 4, thus forming the sides for said fire pot.

20 The receptacle or drawer 3 is equipped with inclined sides, as shown more particularly in Figs. 3 and 4, and has associated externally of the casing 1 a front portion or plate 12, which plate forms a closure for said drawer. The plate 12 is equipped with 25 a means for regulating the draft of the fire, when started, and this means preferably comprises a slidable plate 13 equipped with holes 14 adapted to be brought into alignment with similar holes within the plate 12. There 30 may be any number of such holes as they may be of any desired size and character.

Any desired means for bringing the sets 35 of holes in alignment may be provided, in the present instance headed pin 15 and slot 16 construction being provided, and a means for operating the plate 13, as well as for pulling out the drawer or receptacle 3, is provided, said means in the present instance taking the form of a knob 17. Of course, this 40 construction may be changed, as in practice found desirable.

A means for controlling or closing off the amount of air admitted to the convection 45 passages 4 and 5 is provided below the plate 12. This means comprises preferably a door 18, equipped with side flanges 19, curved as shown, to provide a means whereby said door may be anchored in any desired position, said door being preferably pivoted to the front 50 of the casing 1 by any suitable construction 23, a conventional or other means, in the shape of a chain or other operating means 20 and a ring 22, associated in any preferred manner with the door 18, being provided to raise and lower said door. Of course, this 55 construction is suggestive merely, and in practice may be varied.

When it is desired to use coal, the grate 60 bars 2 are positioned as shown in Figs. 2, 3 and 5, the bars or members 9 being used for this purpose, the drawer or receptacle 3 having previously been removed. The draft 65 openings 14 are opened, and the door 18 closed until the fire has well started, the products of combustion passing upwardly

through the chambers 26 and 11 and above the wall 27 to the stack 6. After the fire has started, the slide 13 is moved by means of the knob 17 to close the openings 14. The door 18 is then opened, permitting the cooler 70 air in the room to enter the flues 4 and 5, passing up the stack 6, cooling the same, and starting convection currents within the building. No other piping of any sort is required, the house, as demonstrated in practice, being heated within a very short time. The amount of heat required is regulated by 75 opening and closing the door 18 the openings 14 being closed at all times except when the fire is started.

In the form shown in Fig. 5, an additional set of openings, 0' of any shape and number, is positioned within the rear wall of the furnace or stove to provide an additional means for permitting the egress of the products of combustion to the stack, in addition to those passing through the chamber 11' in the casing 1', the grate bars 2' and the fire pot 25' being precisely the same as those 80 previously described.

Should it be desired to use wood, the drawer or receptacle 3 is withdrawn from the casing and the grate bars 2 lowered by means of the members 9 to the position shown in Fig. 4, said bars forming side members to hold the wood in place, the fire being built within the drawer 3 after it has been replaced. The draft openings in this case are again used only to start the fire, after 95 which the door 18 is used as previously described.

While I have thus described my invention with great particularity, it will be clear that the construction shown and described may be modified throughout a wide range. I therefore do not propose to be limited to the exact details of construction but reserve the right in practice to make any and all modifications thereof that fall within the scope 100 of the appended claims.

I claim as my invention:

1. In an apparatus of the class described, in combination, a casing, an alternatively wood and coal burning chamber in said casing, means associated with said casing for regulating the draft to said chamber when the fire is started therein, a stack for said casing, and an external cool air circulating chamber in said casing and positioned below said first chamber, for providing external 110 convection air currents and for cooling the products of combustion passed to said stack.

2. In a heating apparatus, in combination, a casing, a fire pot therein for burning coal, a movable set of grate bars associated with said fire pot, and a removable ash pit positioned below said grate bars, said grate bars being adapted when lowered to coact with said ash pit to form a chamber wherein wood may be burned.

3. In a heating apparatus, in combination, a casing, means associated with said casing whereby coal or wood may alternatively be burned therein, a combined draft regulating means and ash pit for said first means, and a set of passages in said casing and positioned externally of said first means.

4. In a heating apparatus, a casing, lower and rear chamber defining walls in said casing, a fire pot in said casing, draft regulating means for said fire pot, a stack for said casing, said rear wall being so positioned in said casing as to define a space for receiving the products of combustion and conveying the same to said stack, said rear wall having also one or more apertures to provide addi-

tional means for conveying said products of combustion to said stack, and draft regulating means for said spaces and said fire pot.

5. In a combined coal or wood burning apparatus, a casing, a fire pot therein, a removable ash pit, a set of grate bars pivotally associated with said fire pot, and adapted to be lowered to form sides for said ash pit so that wood may be burned therein and plural means externally of said casing, and associated with said grate bars, whereby said grate bars may be shaken or lowered, substantially as described.

In testimony whereof I have signed my name to this specification.

CHARLES E. C. EDEY.
